UNITED STATES PATENT OFFICE.

ANDREW CHRISTIANSON, OF BUTLER, PENNSYLVANIA, ASSIGNOR TO STANDARD STEEL CAR COMPANY, OF PITTSBURGH, PENNSYLVANIA, A CORPORATION OF PENNSYLVANIA.

END FOR BOX-CARS.

1,158,444.

Specification of Letters Patent. Patented Nov. 3, 1915.

Application filed February 21, 1914. Serial No. 820,367.

To all whom it may concern:

Be it known that I, ANDREW CHRISTIANSON, a citizen of the United States, and resident of Butler, in the county of Butler and State of Pennsylvania, have invented a new and useful Improvement in Ends for Box-Cars; and I do hereby declare the following to be a full, clear, and exact description thereof.

10 My invention relates to railway car construction and is particularly concerned with the provision of a metal car end which is adapted to be applied to an ordinary wooden box car, either when the car is first 15 constructed or when the end requires repair after injury or otherwise.

The invention has for its object the provision of a car end of this character which is of strong and economical construction, 20 and may readily be applied to any wooden box car without involving any material alteration in the arrangement of the car frame.

A further object is to provide the car end 25 with reinforcing or strengthening struts, the strengthening effect of which is largely concentrated at the points of greatest strain, which serves to reinforce the car against lateral strains and at the same time are so 30 arranged as to permit convenient location of a ventilating door in the end of the car.

A further object is to so construct and arrange the car end that neither the inside nor the outside longitudinal measurement of 35 the car will be changed by the application of my improved car end.

Other objects and advantages of the invention will appear from a description of the details of the construction, one form of 40 which is illustrated in the accompanying drawing, in which—

Figure 1 is an end view of the car showing the invention applied thereto. Fig. 2 is a vertical section on the line 2—2, Fig. 1. 45 Fig. 3 is a horizontal section on the line 3—3, Fig. 1. Fig. 4 is a vertical section on the line 4—4, Fig. 1, and Fig. 5 is a horizontal section on the line 5—5, Fig. 1.

In the embodiment of my invention herein 50 selected for illustration, so much only of the framing of the car is shown as is necessary to illustrate the application of the improvement thereto, including the end sill 1

at the bottom and the transverse carline 2 at the top of the end. The sill 1 may be 55 secured to the center sills and draft sills 3, upon which the flooring 4 rests. Said end sill is also connected to the side sills in the usual manner. The transverse carline 2 is secured in the usual manner to the side 60 plates 5 at the top. The roof structure of the car is indicated at 6 and the roof runway at 7.

The metal car end embodying my invention consists primarily of a transverse sheet 65 or plate 8 extending across the lower portion of the end of the car and an upper transverse sheet or plate 9 riveted to the first along the line 10. In applying the metal end to the car, the corner posts 11 are 70 set back slightly from the end as indicated in Fig. 2, and the sides of the end sheets or plates 8 and 9 are flanged as at 12, Fig. 3, to embrace the corner posts, and as shown in Fig. 3, the wooden siding 13 of the car. 75 The corners are also reinforced by metal straps 14, which are bolted through to the corner posts and to the siding, as well as the side sheathing 15 of the car wall, said bolts also being set in the inside corner straps 16. 80 The upper edge of the upper plate or sheet 9 is bolted to the inner face of the carline 2, and the lower edge of the lower plate or sheet 8 is flanged as at 17, Fig. 2, and carried beneath the flooring 4. The lower edge 85 of the lower end plate is also secured to the end sill by means of an angle plate 18. As shown in dotted outline, Fig. 2, the connection of the corner post with the side plate may be strengthened by means of a gusset 90 plate 19.

In order to reinforce this metal car end against end thrust, and also against lateral strains on the car, two diagonal pressed steel beams or struts 20 are secured across the end 95 face extending from the upper corners of the car end substantially to points adjacent the center of the lower edge of the face or end. These beams or struts are laterally flanged as at 20', Fig. 3, and secured to the 100 end plates 8 and 9 by lines of rivets 21, and the upper ends of said beams are more or less flattened and flared as at 24 and are secured to the outer face of the carline 2 by bolts 25. It is to be understood also, that 105 these upper ends of the reinforcing beams

are offset slightly to allow for the projection of the outer face of the carline 2 beyond the outer face of the metal end as indicated in Fig. 2. These beams or struts 5 not only strengthen the end against side and lateral thrusts, but also unite the upper and lower end plates 9 and 8 together in a unitary structure. To further reinforce the lower portion of the metal end, a transverse 10 beam or strut 26 is provided, flanged at opposite sides as at 27, Fig. 2, and riveted along the junction of the plates 8 and 9 by the same rivets 10 that unite said plates. The ends of this transverse strut are also 15 united with the plates 8 and 9 and with the inner flanges 20' of the diagonal struts 20 by the rivets 21. The lower ends of the diagonal struts 20 are flanged at 28 and are united with the angle plates 18 by the rivets 29.

By the construction above described, it will be seen that when the metal ends are applied to a box car, the inside longitudinal measurement of the car will not be altered 25 and the outside measurement will also remain substantially as before.

In the upper end of plate 9 is cut a door opening 30. On each side of said opening is located a channel bar 31, Fig. 5, secured to 30 the edge of the opening by rivets 32. These channel bars extend down to the junction of the upper and lower end plates and are secured to their ends by the rivets 10 which serve to unite the two end plates and also the 35 flange of the transverse strut 26 with said end plates. The outer flanges 33 of these channel bars form guides to receive inturned flanges 34, Fig. 5, of a sheet metal sliding door 36. The channel bars 31, therefore, 40 serve both as reinforcing struts extending across the upper end plate 9 and also as guideways for said door. The upper edge of the door has an outwardly pressed rib 37 which, when the door is in its upper or 45 closed position, lies within a hood or cap 38 secured to the outer face of the carline 2. This construction in conjunction with a filler block 39 extending across the door opening beneath the carline 2, effectually 50 prevents access of rain or dust to the interior of the car.

The lower edge of the door is provided with a socket 40 to receive a latch 31, Fig. 4, operable from the inside of the car. The 55 door is also provided with a handle bar or bail 36'.

The car end may be provided with the usual ladder, in this case formed of metal uprights 42 and rungs 43, said ladder being 60 secured to the car end by angle plates 44.

From the above described construction, it will be seen that this metal car end consists of the fewest number of parts and all parts consist of simple rolled or pressed sections, 65 which may be readily produced in any roll-

ing mill equipped with roll stands adapted to turn out plates and sections of the sizes here shown.

While I have herein described a particular embodiment of my invention, and particular constructions and arrangement of parts, it is to be understood that the invention may be modified to any desired extent within the scope of the appended claims.

What I claim is:

1. In car construction, the combination with the car frame of a metal end formed of substantially flat sheet metal having its upper edge secured to the carline and having its lower edge flanged and extending beneath and secured to the flooring of the car, and a pair of diagonal struts or beams formed of rolled or pressed sections and extending from the upper corners of the car end to points at either side of the center line 35 of the lower portion of said end, said struts or beams secured throughout their lengths to the outer face of said metal end.

2. In a car construction, the combination with a car frame having its corner posts set 90 back substantially into alignment with the inner face of the carline, of a metal end formed of substantially flat sheet metal having its upper edge secured to the inner face of the carline and being laterally flanged to 95 embrace and be secured to the corner posts, the lower edge of said metal end being secured to the end sill and a pair of diagonal struts or beams formed of rolled or pressed metal sections of channel form, secured at 100 their upper ends to the extremities of the carline and at their lower ends to the end sill at points on either side of the center of said sill, said struts or beams being laterally flanged and riveted throughout their 105 lengths to the body portion of said metal car end.

3. In car construction, a sheet metal car end, consisting of a plurality of flat metal plates extending transversely across the end 110 and riveted together, the side edges of said plates being flanged to embrace and be secured to the corner posts of the car, the upper edge of said metal end being secured to the carline and the lower edge being flanged 115 to extend beneath the car flooring, said lower edge also having means to secure the same to the car sill, a pair of diagonal struts or beams formed of channel sections, extending from the upper corners of said end 120 to points adjacent the center of the lower edge thereof, said struts or beams being riveted throughout their lengths to said metal end.

4. In car construction, a sheet metal car 125 end, consisting of a plurality of flat metal plates extending transversely across the end and riveted together, the side edges of said plates being flanged to embrace and be secured to the corner posts of the car, the up-

- per edge of said metal end being secured to the carline and the lower edge being flanged to extend beneath the car flooring, said lower edge also having means to secure the 5 same to the car sill, a pair of diagonal struts or beams formed of channel sections extending from the upper corners of said end to points adjacent the center of the lower edge thereof, said struts or beams being riveted throughout their lengths to said metal end, and a transverse strut or beam 10 secured to said metal end and extending between said diagonal struts or beams substantially midway of the height of said end.
- 15 5. In a car construction, a metal car end consisting of upper and lower sheet metal plates extending transversely of the end and secured together at their adjacent edges, the sides of said plates being flanged to embrace 20 and be secured to the corner posts of the car frame, a pair of diagonal struts or beams formed of sheet metal channel sections extending from the upper corners of said end to points adjacent the center of the bottom thereof, and riveted throughout to said end 25 plates, whereby said struts reinforce said metal end against end and lateral strains and reinforce the junction between said end plates.
- 30 6. In a car construction, a metal car end consisting of upper and lower sheet metal plates extending transversely of the end and secured together at their adjacent edges, the sides of said plates being flanged 35 to embrace and be secured to the corner posts of the car frame, a pair of diagonal struts or beams formed of sheet metal channel sections extending from the upper corners of said end to points adjacent the center of the bottom thereof, and riveted throughout to said end plates, whereby said struts reinforce said metal end against end and lateral strains and reinforce the junction between said end plates, and a horizontal 40 strut formed of a sheet metal channel section and extending between said diagonal struts along the line of junction between said end plates whereby said junction is further reinforced.
- 45 7. In a car construction, a metal car end consisting of upper and lower sheet metal plates extending transversely of the end and secured together at their adjacent edges, the sides of said plates being flanged to embrace 50 and be secured to the corner posts of the car frame, a pair of diagonal struts or beams formed of sheet metal channel sections extending from the upper corners of said end to points adjacent the center of the 55 bottom thereof, and riveted throughout to said end plates, whereby said struts reinforce said metal end against end and lateral strains and reinforce the junction between 60 said end plates, said upper end plate having 65 a door opening cut therein, channel mem-
- bers secured to said upper plate and extending from the upper edge thereof to a line of junction between the upper and lower end plates, said channel members forming 70 guide-ways for a sliding door covering said door opening.
8. A car end having its body portion formed of flat sheet metal, the lower edge of which is flanged to extend beneath the floor of the car, means extending transversely to said lower edge to secure the 75 same to the car sill of the car, the side edges of said end being formed to embrace and be secured to the corner posts of the car, struts or beams formed of sheet metal sections of channel form extending from the upper corners of said end toward the center of the bottom thereof, said struts having lateral flanges riveted throughout the length thereof to said metal end. 85
9. A car end having its body portion formed of flat sheet metal, the lower edge of which is flanged to extend beneath the floor of the car, means extending transversely to said lower edge to secure the same 90 to the car sill of the car, the side edges of said end being formed to embrace and be secured to the corner posts of the car, struts or beams formed of sheet metal sections of channel form extending from the upper corners of said end toward the center of the bottom thereof, said sections having lateral flanges riveted throughout the length thereof to said metal end, a transverse strut or beam formed of a channel section extending 95 between said first mentioned struts and secured throughout its length to the metal end, a pair of reinforcing channel members secured to said metal end and extending from the upper edge thereof to said transverse strut, a door opening between said 100 channel members, a door for said opening, said channel members forming guideways for said door. 105
10. In a car construction, the combination 110 with a car frame having corner posts set back from the end of said frame, of a sheet metal car end adapted to be secured at its upper edge to the inner face of the carline and having lateral flanges adapted to embrace and be secured to said inset corner posts whereby said metal car end may be applied to the car without altering the longitudinal interior dimension thereof, and transverse struts or reinforcing beams extending across and secured to the outer 115 face of said metal end and between and substantially flush with the outer faces of the car line and end sill. 120
11. In a car construction, the combination 125 with a car frame having corner posts set back from the end of said frame, of a sheet metal car end adapted to be secured at its upper edge to the inner plates of the carline and having lateral flanges adapted to em- 130

brace and be secured to said inset corner posts whereby said metal car end may be applied to the car without altering the longitudinal interior dimension thereof, and transverse struts or reinforcing beams extending across and secured to the outer face of said metal end and between and substantially flush with the outer faces of the car line and end sill and one or more transverse

and reinforcing struts or beams extending 10 between and substantially flush with said first named struts or beams.

In testimony whereof, I the said ANDREW CHRISTIANSON have hereunto set my hand.

ANDREW CHRISTIANSON.
